UNITED STATES PATENT OFFICE.

HARRY LUCHOW, OF COUNCIL BLUFFS, IOWA.

PIPE.

Application filed June 6, 1924. Serial No. 718,282.

To all whom it may concern:

Be it known that HARRY LUCHOW, a citizen of the United States, residing at Council Bluffs, in the county of Pottawattamie and State of Iowa, has invented certain new and useful Improvements in Pipes, of which the following is a specification, reference being had therein to the accompanying drawings.

The invention relates to pipes, and has for its object to provide a device of this character, the bowl of which has its upper edge provided with downwardly and inclined apertures terminating in the chamber of the bowl at points spaced from the upper and lower end of the chamber and forming means for supplying cool air to smoke below the cinders of the tobacco and above the bottom moist end of the tobacco, thereby obviating burning of the tongue or mouth as is now the common difficulty with conventional forms of pipes.

A further object is to provide the upper end of the pipe bowl with a rotatable channeled annular member having one of its flanges overlying the upper end of the bowl and its lower flange disposed in an annular groove in the outer periphery of the bowl, said upper flange being provided with apertures adapted to register with the apertures in the bowl, and to regulate the amount of air admitted upon a rotatable adjustment of the annular channeled member.

A further object is to provide the ends of the stem of the pipe with an annular disposed aperture for admitting air direct to the smoker's mouth for additionally cooling the smoke.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a perspective view of a conventional form of pipe showing the device applied thereto.

Figure 2 is a vertical longitudinal sectional view through the pipe bowl and a portion of the shank thereof.

Figure 3 is a horizontal sectional view

through one end of the stem showing additional air holes.

Referring to the drawing the numeral 1 designates the bowl of the pipe, 2 the shank and 3 the removable stem carried thereby, Pipes as at present constructed and used are objectionable in that the hot smoke enters the smoker's mouth, and often irritates the membranes of the mouth or burns the tongue. To obviate this difficulty the bowl 1 of the pipe is provided with a plurality of downwardly and inwardly inclined apertures 4, which extend downwardly from the upper end 5 thereof and terminate at 6 spaced from the upper and lower ends of the chamber 7 of the bowl, and through which apertures 70 cool air passes, and mixes with the smoke, below the fire within the pipe, consequently the smoke is cooled before it enters the smoker's mouth. By terminating the lower ends 6 of the apertures 4 above the lower 75 end of the chamber 7, it will be seen that they are above tobacco which would become soggy, incident to saliva which flows through the smoke passage 8, and consequently will not become clogged.

Rotatably mounted on the upper end of the bowl 1 is a channeled annular member 9, which member is provided with a horizontally disposed annular flange 10, which registers with the upper end 5 of the bowl, and is provided with a plurality of apertures 11, which normally register with the upper ends of the smoke passages 4, and it will be seen that by rotating the annular member 9 slightly, the amount of air allowed to pass 90 through the air apertures 4 may be regulated, which is particularly advantageous according to the kind of tobacco being used. The annular member 9 has its flange 12 disposed in an annular groove 13 in the outer periphery of the bowl 1, therefore the annular member is securely held on the bowl. Flange 12 may be crimped or forced into the groove 13 in a conventional form of press, therefore it will be seen that the entire annular member may be formed from a single piece of metal.

To additionally cool the air, the stem 3 is provided with an angularly disposed air passage 14, which passage has its intake end 15 spaced from the ends of the stem and its discharge end 16 in the end of the stem where the air will be discharged through the mouth

of the smoker. By spacing the intake end 15 from the end of the stem 3, it will be seen that the lips of the smoker will not close the intake end 15 of the air passage during 5 the smoking operation.

From the above it will be seen that means is provided in connection with the bowl of a pipe whereby additional air will be provided from the atmosphere to smoke passing 10 through a pipe, thereby cooling the smoke and means is provided whereby the volume of additional air may be regulated as desired.

The invention having been set forth what is claimed as new and useful is:

15 1. The combination with a bowl of a pipe having a chamber therein and air passages extending from the upper end of the bowl and terminating in the chamber of the bowl, of an annular channeled member rotatably 20 mounted on the upper end of the bowl, said channeled member having its upper flange

horizontally disposed and provided with apertures normally registering with the upper ends of the air passages, said channeled member having its lower flange inturned and 25 rotatably mounted in an annular groove in the outer periphery of the bowl.

2. The combination with the upper end of a bowl of a pipe, said bowl being provided with air passages extending angularly downwardly 30 from the upper end thereof and terminating in communication with the chamber of the bowl at a point spaced from the lower end thereof, of means for regulating the volume of air passing through said air passages, said 35 means comprising an annular member rotatably mounted on the upper end of the bowl, and provided with apertures normally registering with the air passages.

In testimony whereof I hereunto affix my 40 signature.

HARRY LUCHOW.
